UNITED STATES PATENT OFFICE.

STELLA G. LEWIS, OF OAKLAND, CALIFORNIA.

DESIGN FOR A DOLL.

Application filed October 26, 1925. Serial No. 15,254. Term of patent 14 years.

To all whom it may concern:

Be it known that I, STELLA G. LEWIS, a citizen of the United States, residing at Oakland, in the county of Alameda and State of California, have invented a new, original, and ornamental Design for Dolls, of which the following is a specification, reference being had to the accompanying drawing, forming part thereof.

I claim:

The ornamental design for a doll, as shown.

STELLA G. LEWIS.
